RADIATOR

Filed July 20, 1931

Inventor:

Eugene V. Daily,

By *Milliken, Harley, Byron & Knight*

UNITED STATES PATENT OFFICE

EUGENE V. DAILY, OF LOS ANGELES, CALIFORNIA, ASSIGNOR TO JAMES B. CLOW & SONS, OF CHICAGO, ILLINOIS, A CORPORATION OF ILLINOIS

RADIATOR

Application filed July 20, 1931. Serial No. 551,899.

The invention relates to gas fired heating devices and has reference more particularly to improvements in the specially constructed or vent section of gas fired steam radiators.

5 Radiators of this class usually comprise a series of sections having a combustion chamber disposed within the lower part thereof and the customary water and steam chambers located above the combustion 55 chamber. Within this latter chamber there is positioned a fuel burner and in order to carry off the products of combustion from the burner the radiator is provided with a specially constructed section that is in connection with a vent outlet. Products of combustion arising throughout the length of the lower part of the radiator flow into the specially constructed section and are discharged through the vent outlet. In the 60 operation of such radiators it is not uncommon for a back draft of air to rush down the vent with the result that unless some provision for counteracting this effect is made, the danger arises of the gas flame at the burner being extinguished and the gaseous fuel passing from the burner without burning. Again it is not unusual for a 65 strong up-draft to exist in the vent under certain conditions, creating a strong up-draft in the vent section of the radiator and unless some provision is made to compensate such strong up-draft there is a tendency for the gas flame to be lifted off the burner with the result that the gas flame might be entirely extinguished and unburned gas would 70 then be passing from the burner.

For relieving the effect of the down-drafts and strong up-drafts, radiators of this class have heretofore been equipped with an external and detachable draft diverter or regulator placed in the vent pipe connecting the vent section, which section is located centrally of the length of the radiator, to the chimney or outside atmosphere.

40 45 The present invention is concerned with improvements to the above described method of providing a device for preventing down-drafts or excessive up-drafts from interfering with the normal burning of the gas by incorporating it in the vent section and to

locate the relief opening that is an essential part of a draft diverter in that portion of the vent section that would normally be facing the wall and therefore out of view when the radiator is installed. This would normally bring the relief opening in the same wall of the vent section as the opening provided for vent connection.

A further object is to provide the flue chamber of a vent section with a curved 60 wall so positioned in relation to the vent and relief opening as to function as a baffle for directing down-drafts toward the relief opening.

A still further object is to provide the flue 65 chamber of a vent section with a wall of special configuration, which will be so positioned in relation to the vent and relief opening as to direct the out-going products of combustion toward the vent and the 70 down-drafts toward the relief opening.

With these and various other objects in view, the invention may consist of certain novel features of construction and operation 75 as will be more fully described and particularly pointed out in the specification, drawing and claims appended hereto.

In the drawing which illustrates an embodiment of the device, and wherein like reference characters are used to designate 80 like parts—

Figure 1 is an elevational view, parts being shown in section, of a radiator constructed in accordance with the present invention;

Figure 2 is a fragmentary vertical sectional view taken substantially through the center of the specially constructed vent section, and

Figure 3 is a fragmentary vertical sectional view showing a modified form of construction of the vent section.

Referring to the drawing there is shown in Figure 1 a radiator comprising a plurality of sections 2, 4, 6, 8 and 10, each of the sections comprising, as shown in Figure 2, a steam chamber 12 located within the upper portion of the section and a combustion chamber 14 formed within the lower part thereof. The sections are joined to

gether by means of nipples 16 projecting laterally from the sides of the steam chamber and water chamber 20 and by means of laterally extending side walls 18 projecting 5 from the combustion chamber 14, the water chamber 20 and the steam chamber 12. Each section is also provided with a water chamber 20 located intermediate the combustion chamber 14 and the flue passage 19 10 and defined by the top and bottom walls 22 and 24, respectively. The water chamber of each section has communication with the steam chamber 12 formed in that section by means of the passage 26 and the water 15 chamber of each section is joined as shown in Figure 1 by nipples 16.

Thus when a radiator is assembled the steam chambers of the adjacent sections are in communication with one another by 20 means of nipples 16 and the water chambers are likewise in communication by means of other nipples 16 located therein. The combustion spaces in the various sections are aligned with one another and are closed 25 off at the outside surface of each end section to form a single large chamber extending throughout the length of the radiator in the bottom portion of the same. During the use of the radiator an elongated burner 30 30 is inserted lengthwise of the combustion chamber 14 of the radiator and is supplied with a suitable quantity and quality of fuel for generating steam from the water within the chamber 20. To insure proper combustion it is necessary to supply secondary air to the burner and accordingly this air is supplied through opening 32 located in each section.

Products of combustion forming in the 40 combustion chamber 14 flow upwardly between the various sections of the water chamber 20 and then lengthwise of the radiator through the flue passage 19 into the central vent section 6, which is specially 45 constructed, as shown in Figure 2. The vent section 6 is preferably of the same appropriate configuration as the adjacent sections and contains a second flue passage 34, which does not exist in adjacent sections, formed 50 immediately above the flue passage 19 which is common to all adjacent sections and receives all the flue gasses from flue passage 19. A vent opening 36 in the rear wall of flue passage 34 provides for a vent pipe connection 38 to a chimney or outside air. Also formed in the rear wall of flue passage 55 34 below the vent opening 36 is an atmospheric or relief opening 40. In order to more effectively direct the upward moving 60 products of combustion in flue passage 34 toward the vent opening 36 the lower portion of the rear wall 42 may be curved as in Figure 2, but the directing action is also accomplished when 42 is vertical as in Figure 3.

A feature of the present invention is the particular configuration given to the top and front walls, which in connection with the vertically extending side walls 44 and 46 of flue passage 34 and the vent opening 36 and relief opening 40 serve to complete an effective draft diverter, which effectively protects the combustion of fuel at the burner 30 against disturbance from either a down-draft or an excessive up-draft in 70 the vent pipe connection 38. As shown in Figures 2 and 3 the top wall 48 extends from the vent opening 36 and is curved downwardly merging with an arcuate portion 50 of the front wall of flue passage 34 75 or with what may be described as a portion of more determined curvature. The sloping front wall 52 extends from a point on side walls 18 adjacent the water chamber and unites with the arcuate portion 50, forming a cusp 54, which is positioned directly opposite the atmospheric or relief opening 40.

In operation of the radiator the products of combustion formed by fuel burning at 90 burner 30 rise and flow upwardly between the adjacent sections of the water chamber 20 and then longitudinally through flue passage 19 of the radiator into the central vent section 6. Under conditions of normal 95 up-draft in vent pipe 38 and within section 6 they rise into flue passage 34 and are guided in their movement by means of the various walls referred to until they finally pass from the vent section through the vent 100 opening 36. To direct the rising products of combustion toward the vent opening 36 the baffle 42 is provided, which, in connection with sloping front wall 52, and side walls 44 and 46 form a restricted passage 105 through which the products of combustion must flow before entering the upper portion of the flue chamber 34.

When a back draft flows down the vent pipe 38 and into the vent section the draft 110 diverter which constitutes this invention directs the downwardly flowing air by means of the sloping top wall 48 toward the arcuate portion 50, which is so positioned in relation to the vent opening 36 and atmospheric opening 40 that the drafts will be directed outside the vent section through the atmospheric or relief opening 40, thus preventing the down-draft from passing into the lower portion of flue passage 34. At 115 the same time the flue gases are accelerated in their upward passage in that portion of the flue passage 34 located below the upper end of baffle 42 and the cusp 54 by reason of the siphoning action of the down-draft moving at approximately right angles to that portion of the flue passage located between these two points, which causes the 120 upward moving flue gases to join the down-draft and pass from the vent section with 125 130

the down-draft through the relief opening 40. In this manner back drafts are prevented from effecting the combustion of the fuel at the burner 30.

- 5 When there is an abnormally strong up-draft in the vent pipe 38 the atmospheric or relief opening 40 acts as a draft check by permitting the entrance of air from the room to the upper portion of the flue passage 34, thereby maintaining a normal draft in the lower portion of flue passage 34, which prevents the strong up-draft from disturbing the combustion of fuel at the burner 30.
- 10 15 It is to be understood that I do not wish to be limited by the exact embodiment of the device shown, which is merely by way of illustration and not limitation, as various and other forms of the device will be apparent to those skilled in the art without departing from the spirit of the invention or the scope of the claims.

I claim:

1. A radiator of the class described, having in combination, a vent section and a plurality of adjacent sections communicating with the vent section, said vent section comprising a chamber formed by a curved top wall, oppositely disposed vertical side walls, and a sloping front wall merging with the top wall, a vent connection communicating with said chamber, said chamber having an opening provided in the same wall as the vent connection and leading to the atmosphere, said top wall being curved forwardly and downwardly and finally rearwardly to join with the sloping front wall whereby back drafts from the vent connection striking said curved top wall are directed toward said atmospheric opening.

2. A radiator of the class described, having in combination, a vent section and a plurality of adjacent sections communicating with the vent section, said vent section comprising a chamber having an arcuate top wall extending forwardly and downwardly and merging in an arcuate portion extending rearwardly to simulate a section of an ellipse, a sloping rear wall joining with said rearwardly extending portion, and vertical connecting side walls, an atmospheric opening in said chamber located substantially opposite the arcuate rearwardly extending portion, and a vent connection for the chamber, said curved top wall being located opposite the vent connection and atmospheric opening, whereby down-drafts from the flue are directed toward the atmospheric opening.

3. A vent section of the character described comprising in combination, a flue chamber, a vent connection leading from the rear wall of the chamber, an atmospheric opening provided in said rear wall below

the vent connection, the top wall of the chamber being curved downwardly away from the flue and terminating in an arcuate portion, the side wall opposite the opening being sloping and merging with the arcuate portion to form a convex cusp, whereby said sloping wall directs out-going products of combustion toward the flue and the arcuate portion directs down-drafts toward the atmospheric opening.

4. A vent section of the character described comprising in combination, a flue chamber, a vent connection leading from the rear wall of the chamber, an atmospheric opening in said rear wall below the vent connection, a curved top wall for the chamber, and a front wall, said front wall formed to provide a convex cusp directed toward the opening and merging with the top wall, said front wall serving to discharge down-drafts from the vent through the opening and to direct out-going products of combustion toward the vent connection.

5. A vent section of the character described comprising in combination, a flue chamber, a vent connection leading from the rear wall of the chamber, said rear wall having an atmospheric opening located below the vent connection, the wall of the flue chamber opposite the opening and vent connection having a sloping portion for directing out-going products of combustion toward the vent, and an arcuate portion connecting with the sloping portion and merging in the top wall for directing the down-drafts toward the atmospheric opening.

6. A radiator of the class described, having in combination, a vent section and a plurality of adjacent sections communicating with the vent section, said vent section comprising a chamber formed by a curved top wall terminating in a rearwardly extending portion, oppositely disposed vertical side walls, and a sloping front wall merging with the rearwardly extending portion of the top wall, a vent connection communicating with said chamber, said chamber having an opening provided in the same wall as the vent connection and leading to the atmosphere, the wall having the vent and opening being curved below the opening in a direction toward the sloping front wall to provide a restricted passage for the flue gases.

7. A radiator of the class described, having in combination, a vent section and a plurality of adjacent sections communicating with the vent section, said vent section comprising a chamber including a rear wall having a vent connection and an atmospheric opening, and a top wall, said top wall providing a downwardly concave curved surface merging directly with an arcuate portion also having a concave contour, said portion being positioned diagno-
